(57) **CLAIM**

The ornamental design for an electric duct bank slide box, as shown and described.

DESCRIPTION

FIG. 1 is a perspective view of an electric duct bank slide box showing my new design.

FIG. 2 is a front elevational view thereof, the rear elevational view being a mirror image thereof.

FIG. 3 is a top plan view thereof.

FIG. 4 is a right end elevational view thereof.

FIG. 5 is a left end elevational view thereof; and,

FIG. 6 is a bottom plan view thereof.

The broken line elements in FIG. 1, depicting a series of tubes, are environmental elements and are not a part of my new design.
